INVENTOR,

Clarence L. Martin,

BY

Harry W. Bowen,
ATTORNEY.

UNITED STATES PATENT OFFICE

2,005,233

CIGARETTE HOLDER

Clarence L. Martin, Hazardville, Conn.

Application April 3, 1934, Serial No. 718,811

6 Claims. (Cl. 131—51)

My invention relates to improvements in cigarette holders.

An object of my invention is to provide a cigarette holder in which the cigarette may be completely enclosed without interfering, in any way, with its free burning qualities, but which will retain all ashes and residue of combustion, and prevent contact of the hot ashes, or burning end, of the cigarette with any object which may come in contact with any part of the holder.

A further object of my invention is to provide, in such a holder, means for extinguishing a lighted cigarette therein, so that the cigarette may be partly smoked, the holder closed and immediately placed in a pocket or other convenient place with the cigarette contained therein, without danger of burning or scorching its surroundings.

A still further object of my invention is to provide, in such a holder, means for ejecting the stub of a smoked cigarette, and means for retaining in the holder in the direct path of inhaled smoke a mentholated or otherwise flavored or perfumed capsule, with means for easily and quickly removing or interchanging the capsules.

These and other objects and advantages of my invention will be more completely disclosed and described in the specification, the accompanying drawing, and the appended claims.

Broadly, my invention comprises a mouthpiece or bit member formed with a cavity or recess in which a scented or flavored capsule may be placed and a tapered opening for receiving an end of a cigarette, a sleeve member slidably supported on the bit member over the cavity to normally close the same, in order to retain the capsule in place, but formed with an opening which may be registered with the cavity for removal or replacement of the capsule, means on the sleeve for ejecting a cigarette butt when the sleeve is moved or slid forwardly on the bit member, a second sleeve member secured on said bit member and formed with a plurality of longitudinal slots and provided with an integral reticulated lining, and a cap member formed with longitudinal slots and provided with an integral reticulated lining for a portion of its length and across the end, said cap member being removably and rotatably supported on the second sleeve member normally with its slots registering with the slots in the second sleeve member, but rotatable to close the slots in the second sleeve member.

A preferred embodiment of my invention is illustrated in the accompanying drawing, in which:—

Fig. 1 is a longitudinal, sectional view through the axis of the assembled holder with a cigarette in place therein.

Fig. 2 is a cross, sectional view on the line 2—2 of Fig. 1.

Fig. 3 is a cross, sectional view on the line 3—3 of Fig. 1.

Fig. 4 is a cross, sectional view on the line 4—4 of Fig. 1.

Fig. 5 is a view similar to Fig. 4, but with the sleeves in the opposite relative position for cutting off the external air.

Fig. 6 is a cross, sectional view on the line 6—6 of Fig. 7, and

Fig. 7 is a plan view of the holder with its various parts in disassembled relation.

Referring now to the drawing in detail, in which like numerals refer to like parts throughout:—

A cigarette, 1, has an end 2 thereof located and held in a tapered or bell-shaped socket 3 formed in a mouthpiece or bit member 4. The bit member 4 is formed with a shoulder 5 and a stem portion 6. The stem portion 6 is formed with a cavity or recess 7 for receiving a capsule 8, and a relatively small bore 9 connecting or having communication with the bell-shaped socket 3. The capsule 8 comprises a tubular member 10 containing a loose, fibrous material 11, as asbestos or cotton, which may be scented or flavored to taste. A sleeve member 12 is slidably and rotatably supported on the stem 6, and is formed with an opening 13 and a bayonet slot 14 co-operating with a pin 15 in the stem 6 to hold the sleeve 12 in position for closing the recess 7 and retaining the capsule 8 within the stem 6. The sleeve 12 is also provided with a forwardly extending finger element 16 terminating in an inwardly extending portion 17, against which the butt 2 of the cigarette 1 engages. A tubular member 18 is pressed on the end of the stem 6 and serves to retain the sleeve member 12 on the stem 6 and to limit the slideable movement of the sleeve 12 on the stem 6. The stem 6 is formed with a longitudinal slot 19 and annular slots 20 and 21.

When the sleeve 12 is moved forwardly on the stem 6, the finger 16 and ejector 17 move in the slot 19 and the butt 2 of the cigarette will be ejected from the socket 3. When the sleeve 12 is moved forwardly against a shoulder 22 formed by a notch 23 in the tubular member 18, and rotated to bring the opening 13 in line with the cavity, or recess, 7, the ejector 17 rotates in the slot 20. The slot 21 provides a recess for the ejector 17 to compensate for the slight movement required to lock the sleeve 12 on the pin 15.

A sleeve member 24 is pressed on over the tubular member 18, and overlaps the slots 19 and 21, thereby closing these openings. The sleeve 24 is preferably composed of bakelite, rubber, or other suitable heat resisting material, and is formed with a plurality of longitudinal slots 25 and provided with an integral reticulated lining 26, preferably of wire cloth cast, or molded into 60

the inner wall of the sleeve 24. The sleeve 24 is also formed with a shoulder 27 which butts against the tubular member 18, and the end 28 of the sleeve 24 provides a stop for the sleeve 12. A cap member 29, of bakelite or other suitable heat resisting material, is slidably and rotatably supported on the sleeve 24, and held in either open or closed position by co-operation of a double bayonet slot 30 formed in the cap 29 with a pin 31 secured in the sleeve 24. The cap member 29 is formed with a plurality of longitudinal slots 32 and an opening 33 in an end 34 thereof, and is provided with an integral reticulated lining 35, preferably of wire cloth or the like, cast into the inner wall.

In operation, the cap 29 may be removed and a cigarette inserted in the bell-shaped socket 3. The sleeve 24 is approximately two-thirds the length of a cigarette, which permits the end 1' of the cigarette to be held firmly while inserting the cigarette in the socket 3. The cigarette may be first lighted and the cap replaced, or the cap may be first replaced and the cigarette lighted through the end opening 33. After the cigarette has been approximately one-third consumed, if it is desired to extinguish it, the cap 29 may be rotated on the sleeve 24 to close the slots 32, as indicated in Fig. 5. The wire linings 26 and 35 of the sleeve 24 and cap 29, respectively, serve to retain all ashes and other products of combustion within the holder until the cap 29 is removed, when they may be readily removed. The butt 2 of a cigarette is removed by disengaging the sleeve 12 from the pin 15 and sliding it forward on the stem 6, thus moving the ejector 17 forward sufficiently to disengage the butt of the cigarette from the tapered socket 3. In this forward position of the sleeve 12, it may be revolved to bring the opening 13 into register with the cavity, or recess 7, in which position the capsule 8 may be removed and another inserted. The cavity 7 is then closed by a reverse movement of the sleeve 12. The holder, with a lighted cigarette therein, may be laid on or placed against any surface, inflammable or otherwise, without danger of burning or scorching, or it may be placed in a pocket or pocketbook with perfect safety.

What I claim is:—

1. A cigarette holder comprising, a bit member formed with a tapered socket for holding a cigarette and a cavity opening formed in said bit member, a sleeve slidably and rotatably supported on said bit member for closing said cavity, a capsule for receiving a flavored material in said cavity, means on said sleeve member for ejecting a cigarette from said tapered socket, a second sleeve member secured on said bit member and formed with a plurality of slots, a wire cloth lining in the second sleeve, said second sleeve member enclosing a portion only of a cigarette secured in said socket, a cap member removably and rotatably secured on said second sleeve member and formed with a plurality of slots, and a wire cloth lining in the cap member, whereby when the cap member is rotated on the second sleeve member, the slots in the cap member may be made to register with the slots in the sleeve member or with the wall of the sleeve member between its slots.

2. A cigarette holder comprising—in combination, a bit member formed with an opening there-

through and a recess portion in line with the opening, an open-ended capsule in the recess for receiving a flavoring substance, a slotted sleeve on the bit member to permit the capsule to be inserted, removed, or confined therein, the bit member having a recess with an inclined wall for receiving and retaining an end of a cigarette therein, and means actuated by the slotted sleeve for ejecting the stub portion of a consumed cigarette.

3. A cigarette holder comprising—in combination, a bit member formed with an opening there-through and a recess portion in line with the opening, an open-sided capsule in the recess for receiving a flavoring substance, a slotted sleeve on the bit member to permit the capsule to be inserted, removed, or confined therein, the bit member having a recess with an inclined wall for receiving and retaining an end of a cigarette therein, means actuated by the slotted sleeve for ejecting the stub portion of a consumed cigarette,— the bit member having means cooperating with the slotted sleeve for permitting the said sleeve to be axially movable and rotatable therein, and means connected to the slotted sleeve for extinguishing the cigarette before it is consumed.

4. A cigarette holder comprising a bit member formed with a socket portion in which a cigarette may be inserted and provided with an opening, a capsule removably supported in the opening in said bit member, a sleeve slidably and rotatably secured on said bit member over said capsule and provided with an opening registerable with the opening in the bit member, and a tubular member removably secured on said bit member and completely enclosing a cigarette located in said socket, said tubular member being provided with openings for the introduction of air to said cigarette.

5. In a cigarette holder, a bit member having an opening through the same and a flaring wall portion at its inner end to receive an end of a cigarette, an open ended sleeve connected to the bit member and provided with longitudinal slots and covering only a portion of the cigarette, a second sleeve formed with a closed end and provided with longitudinal slots and located over and connected to the first-mentioned slotted sleeve for rotative movement thereon for extinguishing a cigarette when rotated, said second sleeve extending beyond said first sleeve to enclose a cigarette, and a reticulated lining in said sleeves for receiving the ashes from the cigarette as it burns, said sleeves being formed of heat-resisting material.

6. In a cigarette holder, a bit member provided with an axial opening terminating in a flared socket for holding the butt end of a cigarette and having a second opening in its side wall communicating with said axial opening, the bit member having a longitudinal slot, and a sleeve member slidably and rotatably secured on said bit member and provided with a radial tongue extending through said longitudinal slot in said bit member and into said flared socket, said sleeve member being formed with an opening registerable with the second opening in the side wall of the bit member when the sleeve member is rotated, said bit member being also formed with circumferential slots in which said radial tongue moves when said sleeve is rotated.

CLARENCE L. MARTIN.
